UNITED STATES PATENT OFFICE

2,488,794

DOOR LATCH

Richard T. Anderson, Stacy, Minn.

Application December 23, 1944, Serial No. 569,474

17 Claims. (Cl. 292—126)

1

My invention relates to an improvement in door latch wherein it is desired to provide a latch which is simple to operate and inexpensive to manufacture.

In my previous Patent No. 2,230,476, issued February 4, 1941, for "Door latch," I disclosed a latch of the same general type having a substantially horse shoe shaped handle and a U-shaped bracket supporting the same. The present application has been developed as an improvement of this patent and is designed to overcome some of the manufacturing difficulties which have been encountered in the manufacture of the previous type of latch.

It has previously been proposed to embody in a U-shaped handle a separately pivotal latch element. This combination as previously designed involved certain disadvantages. A spring is required to hold the operating handle in one extreme position. If a separately pivotal latch were provided it was either necessary to employ an additional spring to hold the latch extended or to use a single spring for applying spring pressure both to the handle and to the latch. If the latter construction was employed the retraction of the pivotal latch acting to compress the spring removed spring tension against the handle. Thus as the door swung into closed position retraction of the pivoting latch usually tended to swing the handle in unison with the latch, thus losing most of the benefit of the separately pivotal latch.

It is an object of the present invention to provide a pivoted handle incorporating a separately pivoted latch and to provide a means of applying tension against both of these elements through the use of a separate spring. This spring is so positioned as to continuously apply pressure against both the individually pivoted latch and the handle. As a result the latch may be retracted while spring pressure is still applied against the handle to hold the handle in its normal extreme position.

A further feature of the present invention lies in the provision of an improved lock for holding the latch inoperative. This lock will permit retraction of the individually pivoted latch, but will prevent operation thereof by the handle. As a result the lock may be applied while the door is still open and the door may then be closed without injury to any of the parts.

An additional feature of the present invention lies in the simplicity of the assembly of my door latch. The various parts of the latch are so prepared that they may be easily assembled and held in place by use of a single rivet or pivot bolt. As

2

a result my latch is extremely inexpensive to manufacture and assemble.

A further feature of the present invention lies in the keeper construction used in combination with my latch. This keeper is formed of a single piece of material stamped and formed to produce a keeper which is extremely strong and yet which is inexpensive to manufacture and attractive in appearance.

10 These and other objects and novel features of my invention will be more clearly and fully set forth in the following specification and claims.

In the drawings forming a part of my specification:

15 Figure 1 is a perspective view of my latch showing the construction thereof.

Figure 2 is a plan view of my latch in engaged position, the view showing in dotted outline the relative position of a door and portion of a door frame.

20 Figure 3 is a plan view of the latch in locked position.

Figure 4 is a plan view similar to Figures 2 and 3, but showing the lock in open position and the 25 handle pivoted to disengage the latch.

Figure 5 is a view similar to Figure 4 showing the handle in normal position, but showing the latch in retracted position.

Figure 6 is a sectional view through the lock 30 handle showing the construction thereof.

Figure 7 is a perspective view of a pressure yoke held by spring tension against the handle and latch element.

Figure 8 is a perspective view of a bracket forming a part of the latch mechanism.

35 Figure 9 is an end view of the channel bracket supporting the pivoted handle of my latch.

Figure 10 is a perspective view of the keeper in normal position.

40 Figure 11 is a diagrammatic view showing the blank from which the keeper of Figure 9 is formed.

The latch A includes a handle of U-shape or horseshoe shape as best illustrated in the drawings, pivotally supported in a channel bracket 45 11. The channel bracket 11 is designed to overlie portions of opposed surfaces of a door adjacent a marginal edge thereof, as well as a portion of the edge itself. Thus the latch may be applied by cutting a notch in the marginal edge of the door extending between the opposed door surfaces and fitting the latch mechanism into this notch so that the channel bracket 11 conceals the notched portion of the door.

50 In order to pivotally support the handle 10, I

provide a pair of opposed ears 12 which are bent inwardly toward the interior of the bracket 11. The ears 12 are formed of material ordinarily comprising a part of the channel flange 13 so that by bending the ears inwardly I provide an aperture between the ears through which the handle 10 may extend. An elongated aperture 14 is provided in the opposed bracket flange 15, which overlies the surface of the door opposite that engaged by the flange 13. The base 16 of the channel bracket 11 overlies the door edge.

To reinforce the ears 12 and the pivotal support between the channel bracket 11 and the handle 10, I provide a U-shaped bracket 17 best illustrated in Figure 8 of the drawings. The bracket 17 is provided with a pair of parallel plates 19 and 20 which are connected by a narrower strip 21. The strip 21 is substantially flush with the edges 22 and 23 of the plate 19 and 20, leaving a notch or aperture 24 between the band 21 and the edges 25 and 26 of the plates 19 and 20 opposite the edges 22 and 23. From the edges 25 and 26 vertically aligned ears 27 and 28 which are designed to extend through the aperture 30 formed by the inturning of the ears 12 form the body of the plate 13.

As best illustrated in Figure 6 of the drawings the handle 10 is hollow throughout its length being rolled to provide an inner seam extending about the inside of the handle. This tubular construction of the handle which extends throughout the length thereof lends strength to the structure without materially increasing the weight. In previous constructions the center portion of the handle 10 was not hollow as illustrated and accordingly the present construction is believed advantageous.

Within the center portion of the handle 10 I provide a latch element 31. This element is pivoted at 32 upon a rivet or pivot bolt 33 which extends through the ears 12, through the plates 19 and 20, and through the latch element 31. The latch element is provided with a substantially triangular projecting portion 34 which extends through a slot 35 in the handle 10. A shoulder 36 as well as the extremity 37 of the latch element 31 engage the inner surface of the tubular wall forming the latch element 31 so as to limit projection of this element from the handle. A projection 39 is also provided on the latch element 31 extending into an aperture 40 on the inner side of the handle 10. This projection 39 extends substantially flush with the outer surface of the handle when the latch element is in projecting position and projects through the aperture 40 when the latch is retracted.

A yoke 41, best illustrated in Figure 7 of the drawings, overlies a portion of the inner surface of the handle 10 between the walls 13 and 15 of the channel bracket 11. This yoke 41 is curved to fit the contour of the portion of the handle 10, which it embraces. A plate 42 integral with the trough-shaped body 41 lies substantially flat against the wall 15 of the bracket 11 in normal position.

A locking slide 43 extends through a suitable slot 44 in the plate 15 and is provided with an end in engagement with the bracket 17. The outer end 45 of the slide 43 is curved as illustrated so that it may be easily engaged by the fingers and moved longitudinally. A shoulder 46 is provided in the slide 43 so as to limit slideable movement of the slide 43 in one direction. When the shoulder 46 is in engagement with

the inner surface of the channel wall 15, the outward movement of the slide 43 is prevented.

A flange 47 is provided on the inner end of the slide 43, this flange being of dimensions to slide in the notch 24. The body of the slide 43 adjacent the end 47 engages inwardly of the strip 21 of the bracket 17 and the flange 47 is permitted to move the width of the notch 24 between the strip 21 and the edges 25 and 26 of the plates 19 and 20. In other words, the slide 43 may be moved into the locking position shown in Figure 3 of the drawings, wherein the flange 47 is in engagement with the bracket plate 13. In this position the straight portion 49 of the slide 43 adjacent the curved end 45 will be moved in the path of movement of the plate 42 of the yoke 41, thus locking the handle 10 from pivotal movement.

A spring 50 is interposed between the yoke 41 and the slide 43. This spring acts to hold the locking slide 43 in proper position and also applies spring tension both to the latch element 31 and the handle 10. This spring 50 tends to hold the locking slide 43 in whatever position it is manually placed in. As shown in Figure 2 of the drawings the spring would exert a slight longitudinal pressure upon the slide 43, tending to hold the shoulder 46 against the plate 15 when the slide is in unlocked position. When the locking slide 43 is put in its other extreme position, as shown in Figure 3 of the drawings the spring 50 then exerts a slight longitudinal force tending to push the flange 47 against the flange 13. As a result the spring has an important function in the operation of the locking slide.

The spring 50 also has an unusual function in applying pressure both to the handle and to the latch element 31. As will be noted from Figure 5 of the drawings the retraction of the latch element 31 engages the yoke 41 near the end thereof opposite the plate 42. On the other hand pivotal movement of the handle 10, as shown in Figure 4 of the drawings, causes engagement of the yoke 41 at the end thereof bearing the plate 42. The spring 50 contacts an intermediate point of the yoke 41 so that the yoke may pivot in one direction when the latch element alone is retracted and may pivot in the opposite direction when the handle and latch element are pivoted in unison.

In Figure 4 of the drawings it will be noted that the yoke 41 has pivoted in unison with the handle 10, the plate 42 clearing the straight portion 49 of the locking slide adjacent the shoulder 46. As will be noted from Figure 3 of the drawings this pivotal movement of the handle 10 is blocked by the slide 43 when the slide is in its locking position shown in this figure.

When the latch element 31 is pivoted inwardly by itself as it would in the event the door was closed without engaging the handle, the projection 39 of the latch element 31 engages against the inner surface of the yoke 41 at a point farther from the end of the yoke supporting the plate 42 than the distance between the spring 50 and the plate end of the yoke. As a result the yoke 41 fulcrums about the free edge 51 of the plate 42, as illustrated in Figure 5 of the drawings. The spring 50, however, still exerts tension against the handle 10, tending to hold the handle in normal position.

In other words, the yoke 41 may pivot about either end thereof as a fulcrum and spring pressure is applied between the points of engagement 75 of the yoke with the latch element and with

the handle. Thus should either of these elements tend to pivot separately spring pressure is still applied against the other.

In order to permit the spring 50 to assume a considerable angle relative to the slide 43 and the yoke 41, I provide a raised bearing 52 on both the yoke 41 and the slide 43 against which the ends of the spring may engage. The spring is held in place by a central protuberance 53 which extends into the interior of the spring to hold the same in its proper position.

The keeper B is of the construction shown in Figures 10 and 11 of the drawings. The keeper is provided with a plate 54 having spaced apertures 55 therein. A plate 56 extends at an acute angle to the plate 54 and triangular portions 57 on the plate 56 are bent at right angles to the plate 56 and engage against the plate 54. As a result a wedge-shaped aperture is provided within the keeper into which the triangular projection 33 of the latch element 31 may extend. Screws 59 extend through the apertures 55 to hold the plate 54 against the door jamb 60 and an additional screw 61 may extend through an aperture 62 in the plate 56 if it is desired to better secure the keeper.

The operation of my latch as described in connection with the construction thereof is believed obvious. The latch is applied by cutting a notch in the edge of the door and inserting the latch into this notch so that the channel bracket 14 embraces the edge and adjacent side surfaces of the door. The spring 50 normally holds the projecting portion 33 of the latch element 31 in engagement with the keeper B. By pulling upon the end 63 of the handle 10, or by pushing upon the end 64 of the handle 10, the handle may be swung in a clockwise direction as viewed in Figures 2 through 6, pivoting the latch element out of engagement with the keeper. Upon pivotal movement of the handle 10, the yoke 41 and its attached plate 42 swing with the handle. Pivotal movement of the handle tends to compress the spring 50 and therefore this spring tends to return the handle and its latch to normal position illustrated in Figure 2. When it is desired to prevent pivotal movement of the handle, the locking slide 43 may be moved into the position shown in Figure 3 of the drawings, thereby preventing the yoke 41 from swinging and locking the handle from pivotal movement. As shown in Figure 5 of the drawings, the latch element may pivot independently of the handle, this movement swinging the yoke 41 about the end of the yoke supporting the plate 42, thus compressing the spring 50. The spring then exerts its force against both the handle 10 and the latch element 31, holding the handle in normal position while allowing the latch element to retract.

In accordance with the patent statutes, I have described the principles of construction and operation of my door latch, and while I have endeavored to set forth the best embodiment thereof, I desire to have it understood that obvious changes may be made within the scope of the following claims without departing from the spirit of my invention.

I claim:

1. A door latch comprising a frame, a curved handle pivotally secured in said frame, an independently pivotal latch element, a spring urged yoke engageable against said handle and pivotal relative thereto, and means on said latch element engageable with said yoke, said yoke continuously exerting spring pressure both against

said latch element and said handle regardless of the relative positions thereof.

2. A door latch comprising a frame, a curved handle pivoted to said frame, an independently pivotal latch element, a yoke engaging said handle and said latch element and pivotal relative thereto, and spring means engaging said yoke to continuously urge the same against said latch element and said handle regardless of the relative positions thereof.

3. A door latch comprising a frame, a curved handle pivoted to said frame, a yoke engaging against said handle at a point spaced from the point of pivot, an independently pivotal latch element, said latch element engaging said yoke at a point nearer the point of pivot of said handle from the part thereof engaged by said yoke, and spring means engaging said yoke between the point of pivot with said latch element and the point of engagement with said handle to continuously exert spring pressure against the handle and latch element.

4. A door latch comprising a frame, a door handle pivotally secured to said frame, a latch element independently pivoted coaxial with the handle pivot, a yoke engaging said handle and pivotal relative thereto, means on said latch element engaging said yoke, and spring means urging said yoke against said handle and latch element, said spring means engaging said yoke at a point spaced from said pivot a distance greater than the distance between said pivot and said means on said latch element to continuously exert spring pressure against the handle and latch element.

5. A door latch comprising a frame, a curved handle pivotally supported by said frame, an individually pivoted latch element, a yoke engaging against said handle, means supporting said yoke pivotal with said handle and pivotal with respect thereto, means on said latch element engageable with said yoke to pivot the same independently of said handle, and spring means engageable with said yoke to continuously urge the same against said handle and said latch element regardless of the relative positions thereof.

6. A door latch comprising a frame, a curved handle pivotally supported by said frame, a latch element pivotally secured coaxial with said handle, a pressure plate engaging said handle to resist pivotal movement thereof, spring means urging said pressure plate against said handle, means on said latch element engageable with said pressure plate, pivotal movement of said latch element relative to said handle moving said pressure plate said spring means continuously exerting pressure against both said latch element and said handle.

7. A door latch comprising a frame, a handle pivotally supported by said frame, a pressure plate engaging said handle to resist pivotal movement thereof in one direction, a pivotally supported latch element pivotal relative to said handle, means on said latch element engageable with said pressure plate, pivotal movement of said latch element relative to said handle acting to pivot said pressure plate relative to said handle, and spring means constantly urging said pressure plate simultaneously against both said handle and said latch element.

8. In a door latch, a frame including a pair of substantially parallel sides, a curved handle pivoted to said frame, a locking slide supported between the sides of said frame and movable laterally, cooperable locking means on said handle

engageable with said slide in one position thereof to hold said handle from pivoting, said locking means pivoting past said slide in another position thereof.

9. In a door latch, a frame including a pair of substantially parallel sides, a curved handle pivoted to said frame, a slide movable laterally of said frame, said slide projecting beyond one of said sides of said frame, spring means interposed between said slide and said handle to urge said handle in one extreme position, shoulder means on said slide, and means on said handle engageable with said shoulder means in one position of said slide to hold said handle from pivotal movement.

10. In a door latch, a frame including a pair of substantially parallel sides, a handle pivotally secured to said frame, a slide supported by said frame extending transversely of said frame and movable between two extreme positions, cooperable means on said handle and said slide engageable in one extreme position of the slide to lock the handle from pivoting, spring means interposed between said slide and said handle to resist movement of said handle in one direction, said spring means holding said slide in either extreme position.

11. A door latch comprising a frame, a handle pivotally secured to said frame, an independently pivotal latch element supported by said handle, a slide supported by said frame extending transversely of the frame and movable between two extreme positions, cooperable means on said handle and said slide engageable in one extreme position of the slide to lock the handle from pivoting, spring means interposed between said slide and said handle, said spring means exerting pressure against said handle and said independently operable latch element, and holding said slide in either extreme position.

12. A door latch comprising a frame, a handle pivotally secured to said frame, a pivotally supported latch element, a slide transversely supported by said frame and movable between two extreme positions, cooperable means on said handle and said slide engageable in one extreme position of the slide to lock the handle from pivoting, a spring interposed between said slide and said handle, and spring urged means interposed between said spring, said handle and said latch element to exert spring pressure against both said latch element and said handle.

13. In a latch, a channel bracket, a curved handle extending through opposed sides thereof and pivoted thereto, a slide movably mounted substantially parallel to the base of said channel bracket and movable between two extreme positions, spring means interposed between said handle and said slide, means on said handle engageable with said slide in one extreme position thereof to limit pivotal movement of said handle, said spring resisting pivotal movement of said handle and acting to hold said slide in either extreme position.

14. A door latch comprising a channel bracket, a curved handle extending through opposed sides of said bracket and pivotally secured thereto, an

independently pivotal latch element supported by said handle, a slide extending between opposed sides of said bracket substantially parallel to the base thereof, cooperable means on said handle and said slide engageable in one extreme position of the slide to lock the handle from pivoting, a spring interposed between said handle and said slide, and means interposed between said spring and said handle and said latch element to distribute spring pressure between said latch element and said handle.

15. A door latch comprising a channel bracket, a handle extending through opposed sides of said bracket and pivotally secured thereto, an independent pivotal latch element supported by said handle, spring means supported by said bracket and engageable with said handle and said latch element, said spring means constantly resisting pivotal movement of said handle simultaneously resisting independent pivotal movement of said latch element.

16. In a door latch, a plate designed to overlie a surface of a door, said plate having an aperture therethrough, a pair of ears extending in substantially parallel relationship at substantially right angles to said plate on opposite sides of said aperture, a handle means extending through said aperture, a pivot extending through said ears and through said handle to pivotally connect said handle to said plate, a spring bracket comprising a pair of arms and a connecting base, said pivot extending through said arms and forming a support for said bracket, spring means, and means on said base of said spring bracket supporting one end of said spring, the other end thereof exerting a biasing force against said handle to normally urge said handle in one direction.

17. A door latch comprising a plate designed to overlie a surface of a door, an aperture in said plate, a pair of ears extending inwardly from said plate in substantially parallel relationship on opposite sides of said aperture, a handle member extending through said aperture, pivot means extending through said ears and through said handle to pivotally support said handle, a spring bracket comprising a base and a pair of arms through which said pivot extends, a relatively pivotal latch member pivotally supported by said pivot, spring means interposed between the base of said bracket, said relatively pivotal latch member and said handle, and means on the base of said spring bracket supporting one end of said spring means, the other end of said spring acting to urge both said relatively pivotal latch member and said handle in one rotative direction.
